Primary Examiner — Bridget L Eland*Assistant Examiner* — Lauren McVey(74) *Attorney, Agent, or Firm* — Design IP(57) **CLAIM**

The ornamental design for a device tilter, as shown and described.

DESCRIPTION

FIG. 1 is a perspective view of a device tilter showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dash-dotted broken lines on the bottom surface in the FIG. 7 view represent the bounds of the claim and are not included in the claim, while all other evenly spaced broken lines are directed to environment and are for illustrative purposes only; the broken lines form no part of the claimed design. In addition, the unshaded surfaces throughout the views that directly adjoin the claimed solid line edges shown in the views form no part of the claimed design.
